Primary Examiner — Karen S Acker*Assistant Examiner* — Wendy Arminio(74) *Attorney, Agent, or Firm* — Adam K. Sacharoff; Much Shelist(57) **CLAIM**

The ornamental design for a lid, as shown and described.

DESCRIPTION

FIG. 1 is a top, right side perspective view showing the new design for a lid in a closed position;

FIG. 2 is top, front perspective view thereof;

FIG. 3 is a left side perspective view thereof;

FIG. 4 is a front elevation view thereof;

FIG. 5 is a rear elevation view thereof;

FIG. 6 is a left side view thereof;

FIG. 7 is a right side view thereof;

FIG. 8 is a top plan view thereof;

FIG. 9 is a top, rear perspective view thereof in an opened position;

FIG. 10 is a top, front, left side perspective view thereof;

FIG. 11 is a top, front, right side perspective view thereof;

FIG. 12 is a front elevation view thereof;

FIG. 13 is a rear elevation view thereof;

FIG. 14 is a left side view thereof;

FIG. 15 is a right side view thereof; and,

FIG. 16 is a top plan view thereof.

The broken lines shown in the drawings depict portions of the lid that form no part of the claimed design.
